UNITED STATES PATENT OFFICE.

LOUIS GALE, OF CLEVELAND, OHIO.

COMBINATION CHEMISE AND BLOOMERS.

Application filed September 8, 1927. Serial No. 217,338.

This invention relates to combination chemise and bloomers, and refers especially to loose underwear having the desirable qualities of being formed of two elongated pieces whose upper lateral edges are attached by vertical seams to provide the chemise part, and a portion of the lower edges attached by seam to divide the lower part into the leg portions of the bloomers. 5 It is characteristic of this garment that both leg portions shall have their edges unattached at the outer sides, though they are arranged in overlapping relation, the result being a comfortable garment for the wearer, providing the loose bloomer with more than ordinarily full leg portions, though the bloomer may be substantially uniform in size with that of the chemise portion. It is a special object of my invention to provide such garment having cuffs for the bloomer parts detachably connected by suitable fasteners in alinement with the unattached edges of the leg portions, so that the opening of the cuffs shall be wholly at 25 the outer lateral portions.

It is a further object of my invention to provide the combined chemise and bloomer garment having both front and rear strips continuous from the top of the chemise as 30 applied to a form with the added strips attached to the leg portion and the lateral opening shown slightly.

With these and other objects that will appear as the description proceeds, my combined garment consists of the arrangement and combination of parts explained in the following description, recited in the appended claims, and illustrated in the accompanying drawings, in which—

40 Figure 1 is a view of the garment shown upon the human figure in a sitting position, and showing the cuff opened by detaching the fastener;

Figure 2 is a side elevation of the garment as applied to a form with the lateral opening shown slightly divided;

Figure 3 is a similar view, but showing the edges of the leg portion shown in overlapped relation;

50 Figure 4 is a transverse section of the garment shown in a plane indicated by the line 4—4 of Fig. 2;

Figure 5 is a transverse section of the garment shown in Fig. 3 as taken on the line 5—5 of that view;

55 Figure 6 is a rear elevation of the garment

as indicated suspended from the upper edge thereof, and one of the cuffs opened by unfastening the hook, and

Figure 7 is a front elevation of the garment modified somewhat by the attachment of an apron portion attached at its upper edge to the waist seam.

In the drawings, similar reference numerals refer to similar parts throughout the several views in which the numeral 5 designates the camisole portion of my garment and 6 the bloomer portion generally. The front and rear strips have each a lower and upper portion of almost equal length, and 70 integrally shown at 7 and 8, respectively. The lateral edges of the part 5 are connected together at the seams 13.

The lower edges of the portion 6 are cut out intermediate the lateral edges to form 75 the closed portion by the seam 9. The remainder of the lower edges are unattached to form the cuffs 10. Outside the integral portions 7 and 8, the parts 5 and 6 are connected together by lateral and horizontal 80 waist seams 14 and the leg portions of the bloomers are divided at the outer lateral parts by separated vertical edges 15. Before closing the seams 14, 15 the edges are withdrawn from alinement with the seams 13, 85 thereby forming pleats 16 perpendicular to the seam 14.

To provide for meeting the resulting condition, that of separating the edges of the material at the lateral openings of the 90 bloomers, vertical strips 4 are secured laterally to the part 6 by the seams 15, the outer edges 11 of the strips 4 being bound, and said strips being wide enough so that said edges 11 will overlap as shown in Fig. 3, and 95 secured at their upper ends to the part 5 at the seam 14 in over-lapping relation, but unattached with each other throughout their length, their lower ends forming portions of the cuffs 10. It is at this lower end of the 100 said strips 4 that the cuffs including the strips are detachably fastened by hooks and eyes 12, as shown clearly in Fig. 6. The very decided advantage results in a combined chemise and bloomer having integral front and rear portions of substantially 105 equal length with open lateral leg portions which include the condition of fuller portions and yet retains overlapping relation of the unattached edges at the lateral openings.

The entire garment may be suspended

from the shoulders of the wearer by straps 18 attached to the upper edge 17 of the part 5.

My novel garment may be modified in several particulars and still embody in it the same inventive idea thus far described. Various qualities of material, both as to texture and weight, may be used for manufacture of the garment, and such variations may make desirable slight changes in certain details of manufacture. I have shown in Fig. 7 substantially the same garment, but having attached by the waist seam 20 at the front, a loose apron 19 which may extend downward to any desired length. The seam 20 will follow the seam 14 laterally as far as the seams 13, and will otherwise be in alignment with seams 14. This apron attachment will be found desirable when the main parts of the garment are of especially light weight material, though the garment may be used with or without the apron.

Having thus described my invention, what I claim as new and desire to secure by Letters Patent, is:—

1. A combination chemise and bloomer formed of two main strips of material, each integral throughout their entire length, connected together by lateral seams throughout the upper half of their length, and unattached at their outer, lateral edges throughout the bloomer portion, but connected at their lower edges through the intermediate part thereof, thus providing cuff openings at

either side of the lower end of the garment, 35 limited, horizontal seams connecting the upper and lower portions of the garments at the upper end of the said unattached edges of the bloomers, narrow strips of material 40 of the length of the bloomers being attached to the said unattached edges of said bloomer portions, and to said horizontal seams but not to each other, thus providing an open slit between overlapping edges at the outer 45 part of each leg portion, the cuff openings and said narrow strips being detachably fastened together by hooks and eyes.

2. A combination chemise and bloomer garment comprising, a chemise suspended from the shoulders, bloomers suspended integrally from the chemise at front and back portions, and at the outer, lateral portions by horizontal seams, the legs of the bloomers having cuffs at their ends and vertical outer slits throughout their length terminating at 55 the cuffs, the latter provided with elastic material for yielding attachment about the leg, but formed with detachable fasteners to readily open either cuff, and the edges of each said slit having additional strips of material attached thereto to render the leg portions fuller, the said additional strips being detachably connected together at their lower ends by the same fastener that closes the 60 cuffs.

In testimony whereof I hereunto affix my signature on this the 22nd day of July, 1927.

LOUIS GALE.
